AUTOMATIC FREQUENCY CONTROL
CIRCUITS

Murray G. Crosby, Upper Montclair, N. J., assignor to Radio Corporation of America, a corporation of Delaware

Application March 8, 1946, Serial No. 652,912

4 Claims. (Cl. 250—36)

1

My present invention relates to frequency control circuits, and more particularly to an automatic frequency control (AFC) circuit of the type generally responsive to a shift in frequency of alternating current energy from a predetermined reference frequency value.

One of the important objects of my present invention is to provide an improved and all-electronic AFC system of the type disclosed and claimed in my U. S. Patent 2,379,689, granted July 3, 1945. The prior systems in which the detected output of a discriminator is applied directly to the reactance tube, require the continuous presence of the controlled oscillator and the reference oscillator to maintain the proper in-tune condition (the reference oscillator is the stable oscillator in the transmitting case, and the incoming signal in the receiving case). Absence of either oscillator in the control circuits allows the oscillator to shift to the off-frequency condition it would have taken in the absence of the control system.

As far as I know, this case is the first all-electronic type of automatic frequency control system which applies a correction voltage to the reactance tube that does not allow the oscillator to drop back to its drifted position in the absence of the control potential. This type of operation is a necessity in radio telegraph reception, since it leaves the receiver in proper tune when the transmitter goes off the air.

Another important object of this invention is to provide a frequency control system, adapted for example for use as a servo-mechanism, wherein the system utilizes solely electronic units and is not limited by inertia effects.

Another important object of my present invention is to provide an AFC system which is more flexible of adjustment than the system shown in my aforesaid patent, and which is readily applicable to frequency-shift keying.

Yet another object of my invention is to provide an AFC system wherein a condenser is charged an amount which, when applied to a reactance tube, corrects detuning.

A more specific object of the present invention is to provide a frequency control system of the all-electronic type wherein there is utilized a charging capacity to provide AFC bias for an electronic reactance tube, the charging condenser being under the control of a pair of rectifiers which are normally biased to cut-off to prevent change of voltage across the charging capacity, and the voltage across the charging capacity being a function of space current flow in said rectifiers in response to a frequency shift of control energy from a predetermined reference frequency.

Still other features and objects of my invention will best be understood by reference to the

2

following description, taken in connection with the drawing in which I have indicated diagrammatically several circuits whereby my invention may be carried into effect.

5 In the drawings:

Fig. 1 illustrates a system for receiving radio signals embodying the invention;

Fig. 2 illustrates modifications required to be made in the system of Fig. 1 in order to have it 10 applicable to a transmitter of frequency modulated (FM) signals;

Fig. 3 graphically explains the functioning of the diodes 51 and 52;

Fig. 5 shows a modification of the invention;

Fig. 5 explains the operation of the modification in Fig. 4;

Fig. 6 shows still another modification; and

Fig. 7 explains the operation of the modification of Fig. 6.

20 Referring now to Fig. 1 of the accompanying drawing, in which certain of the networks are schematically represented, I have shown my present AFC system applied to a receiver of a well known form. Generically, there is shown an oscillator 1 having a resonant tank circuit 2. The latter is provided with a tuning, or frequency selecting device 3. The oscillator, which may be considered as operative in any suitable and desirable frequency range, feeds its oscillations to a network 4 designated as a converter. The latter network 4 is to be understood as schematically indicating the converter of a superheterodyne receiving system. As is well known to those well skilled in the art of radio communication, the 25 converter 4 will have an input electrode connected to a suitable source of signals. The converter output energy, in the form of signal modulated oscillations whose mean frequency is the difference between the signal frequency and that of the frequency of tank circuit 2, is applied to a selective amplifier 5 having input and output circuits each tuned to the aforesaid mean frequency. The numeral 6 designates the tuned output circuit of selective amplifier 5.

30 The numeral 7 denotes a transmission path feeding a utilizing circuit with the output energy of the selective amplifier 5. As the system is assumed to be a superheterodyne receiver, the oscillator 1 will be the usual local oscillator which 35 is tunable by the tuning condenser 3 over a range of desired oscillation frequencies. The network 4 will, therefore, be the conventional first detector or converter whose tunable input circuit is adjustable over a range of carrier frequencies. The 40 converter output circuit will be fixedly resonated to the intermediate frequency (I. F.) value of the superheterodyne receiver, while amplifier 5 will in that case be tuned to the operating I. F. value as will, also, be the resonant output circuit 6.

45 The path 7 may then feed the I. F. energy to addition

tional I. F. amplifiers, and the latter will usually be followed by a demodulator, audio frequency amplifiers and a final reproducer.

In Fig. 2 I have shown the modifications required for the invention to be applied to a transmitter, and more particularly an FM transmitter. In such case the master oscillator 1' is provided with tank circuit 2 and tuning capacitance 3. The oscillator output may be transmitted over lead 2' to an amplifier, frequency multiplier and signal radiator (all not shown since they are well known). The converter 4' would now be fed with oscillations from master oscillator 1', and, instead of signals as in Fig. 1, energy from a stable reference oscillator 1'' which may be a crystal-controlled oscillator. Selective amplifier 5' would then have the I. F. energy output of converter 4' applied thereto, and there would be no need for the output connection 7 for amplifier 5'. It is to be clearly understood that the remaining circuit elements now to be described in Fig. 1 are equally applicable to the FM transmitter of Fig. 2.

In either system, whether receiver or transmitter, there is developed at circuit 6 modulated carrier frequency energy. The carrier frequency may be in the kilocycle (kc.) range or in the megacycle (mc.) range, and the character of the modulation may be either amplitude or frequency. As is well known in present day superheterodyne receivers, a change in oscillator frequency is concurrently accompanied by a change of the frequency of the converter selective output circuit. The resulting I. F. signal output energy is not accurately tuned in unless its mean frequency is equal to the predetermined resonant frequency of circuit 6.

The AFC circuit responds to a frequency difference between the I. F. signal energy and the predetermined I. F. value to vary the oscillator tuning in a sense, and to an extent, such as to cause the frequency difference to be reduced. Similarly, in the case of a transmitter, a change in the constants of master oscillator 1' may cause a frequency difference to exist between the predetermined frequency value of amplifier 5' and the mean frequency of the modulated carrier energy output of the amplifier.

A well known form of AFC detector, or discriminator-rectifier, is shown coupled to circuit 6. The function of the AFC detector is to provide a control voltage for AFC purposes in response to a predetermined frequency shift of the carrier of the modulated wave energy applied to circuit 6. The specific form of circuit shown in the AFC detector is that disclosed and claimed by S. W. Seeley in his U. S. Patent 2,121,103, granted June 21, 1938. Accordingly, the action of the AFC detector will not be described in detail, reference being made to that patent. It is to be clearly understood, however, that any other suitable and well known form of AFC detector may be utilized to provide the control voltage which is representative of the frequency shift of the signal energy at output circuit 6.

It will be sufficient for the purposes of this application to explain that a resonant circuit 8, tuned to the same frequency as circuit 6, is magnetically coupled thereto. A direct current blocking condenser 9 is connected directly from the high alternating potential side of circuit 6 to the mid-point of the inductance 8' of secondary circuit 8. The diode rectifiers 10 and 11, which are specifically shown as provided by the electrodes of a duo-diode type tube, are arranged in polarity opposition. The anodes of the diodes are con-

nected to respective opposite sides of the common input circuit 8. The cathodes are connected by a center-tapped resistor which is thereby divided into series-connected load resistors 12 and 12'. Each of load resistors 12 and 12' is bypassed for carrier frequency currents by a respective shunt condenser.

The cathode end of resistor 12' is grounded, and the junction of load resistors 12 and 12' is connected back to the mid-point of coil 8' through a path consisting of high frequency choke coil 13. The numeral 13 designates a source of low frequency current. For example, the latter may be the usual 60 cycle line current employed to energize the various electron discharge tubes of the system. The invention is not limited to the use of 60 cycle current, and it is to be clearly understood that any other value of low frequency may be used in place of the specific 60 cycle value.

When the mean frequency of the applied modulated carrier energy is equal to the predetermined frequency of each of circuits 6 and 8, the radio frequency voltages applied to the rectifiers 10 and 11 will be of equal magnitude. This relationship exists by virtue of the construction of the discriminator input network, and has been explained in detail in the aforesaid Seeley patent. The equal radio frequency voltages applied to rectifiers 10 and 11 are rectified, and equal direct current voltages are developed across resistors 12 and 12'.

On the other hand, if the mean frequency of the applied modulated carrier energy departs from the predetermined reference frequency in one direction, one of the rectifiers will receive more radio frequency voltage than the other. Hence, the direct current voltage developed across one of the load resistors is greater than that across the other resistor. The differential output across the entire output resistor path 12, 12' will then no longer cancel so that the voltage at the cathode end of resistor 12 will have a magnitude and polarity which will respectively depend upon the extent and direction of the shift of the signal frequency at circuit 6 with respect to the predetermined frequency of circuits 6 and 8.

In my aforesaid patent there was utilized a two-phase motor of variable speed and variable direction for controlling the frequency of an oscillator tank circuit. In my present application the system is all-electronic, and is not limited by the inertial effects. In my all-electronic type of AFC there is applied to the reactance tube a correction voltage that does not allow the oscillator 1 to drop back to its drifted position in the absence of the control potential. Where the receiver is employed in radio telegraph reception the present invention is virtually a necessity, as it leaves the receiver in proper tune when the transmitter goes off the air. Additionally, my system is more flexible of adjustment. These various advantages are secured by means of the circuits now to be described in detail.

The AFC detector is followed by an electron discharge device which functions as a phase reverser, and is of the pentagrid tube type. The cathode 16 of the tube 15 is connected to ground through the cathode bias resistor 17, while the first grid 18 is coupled by condenser 19 and resistor 20 to the grounded end of load resistor 12'. It will be observed that the ungrounded terminal of the 60 cycle current source 14 is connected by lead 21 to the ungrounded end of resistor 20. Hence, the 60 cycle current source 14 is shunted across resistor 20, and the potentiometer slider 22 is provided for adjusting the magnitude of the

60 cycle voltage which may be applied over lead 23 to the third grid 24 of tube 15.

The grids 18 and 24 both have 60 cycle voltage applied thereto. The grid 18 has the entire alternating current voltage across resistor 20 applied thereto through condenser 19, while the grid 24 has a predetermined fraction of the voltage across resistor 20 applied thereto. In addition, control voltage, which is direct current voltage, is applied to grid 18 by means of the path consisting of resistor 25, lead 26 and resistor 27. In other words, the grid 18 returns to the grounded end of cathode resistor 17 through a path consisting of resistor 27, lead 26, resistor 25 and load resistors 12 and 12'. The lower end of resistor 27 is bypassed to ground by condenser 30 for alternating currents.

The third grid 24 is surrounded by a positive shielding field by virtue of the fact that the second and fourth grids of tube 15 are connected in common to a source of positive voltage through the resistor 31. The fifth grid of the tube is preferably connected to the cathode 16, and the plate 32 is connected through the output resistor 33 to the +B terminal of the positive source of voltage.

If the voltage at the cathode end of resistor 12 is zero, it corresponds to the condition that the mean frequency of the modulated high frequency energy at circuit 6 is equal to the predetermined reference frequency of circuits 6 and 8. Hence, the direct current voltage of grid 18 is determined solely by the voltage drop across cathode resistor 17. The slider 22 is adjusted to a point on the potentiometer resistor 20 such that when zero control voltage is applied to grid 18, the 60 cycle voltages on grids 18 and 24 have equal effect on the space current flowing to the plate 32. Hence, the 60 cycle voltage developed across resistor 33 is zero in magnitude for that condition of the control voltage developed by the AFC detector. The 60 cycle voltage developed across resistor 33 will change correspondingly in phase and amplitude in response to the variations of magnitude and polarity of the voltage at the cathode end of resistor 12. Hence, I have designated tube 15 as the "Phase reverse" tube to indicate that it functions to provide a 60 cycle voltage at its output terminals whose phase and amplitude are a function of frequency shifts of the modulated high frequency energy at circuit 6.

Pentagrid amplifier 15 is a negative transconductance type of tube with the screen 24' unpreserved, and acts as two amplifiers in cascade with reference to the first control grid 18. The first grid 18 and the screen 24' act as a triode. Screen resistor 31 acts as the plate resistor in this first triode circuit. For the elements comprising the screen 24' and plate 32, the screen constitutes the control grid of a second triode which amplifies the voltage appearing across resistor 31. Thus, in effect, the insertion of a resistor in the screen circuit forms a combination of two triodes in cascade, so that the voltage fed to the first grid goes through one phase reversal for each of the triodes. Hence, a complete 360° rotation is obtained by the first grid 18 and the output plate 32.

The second grid 24 operates in conjunction with plate 32 as a simple pentode, with the single phase reversal of such an amplifier. Hence, when voltage with the same phase is fed to grids 18 and 24, the amplified voltages of the two grids oppose in the plate circuit 32, 33. Consequently, by properly adjusting the relative magnitudes of the

voltages fed to the two grids by means of potentiometer 20, complete cancellation is obtained in the output circuit 33. When a control potential is applied to grid 18, through lead 26 and resistor 27, the relative amplifications of the two grids are upset so that complete cancellation in the plate circuit no longer takes place. The direction and magnitude of the control voltage determines the polarity and magnitude of the voltage due to the unbalance which appears in resistor 33. Hence, a positive control voltage produces one phase of output voltage, and a negative control voltage the opposite phase. The result is a phase reversal.

15. The tube 40, shown as of the pentode type, is an amplifier, and functions to amplify the 60 cycle voltage developed across resistor 33. The cathode 41 of tube 40 is connected to ground through the biasing resistor 42, and the input grid 43 is connected by the coupling condenser 44 to the plate end of load resistor 33. It is noted that the resistor 45 returns the grid 43 to the grounded end of biasing resistor 42. The plate 46 of amplifier tube 40 is connected through the primary winding 47 of transformer T to a source of positive voltage +B. The screen grid of tube 48 may be connected to the same voltage source through the resistor 49, being bypassed to ground for alternating current by condenser 49.

30. The amplified 60 cycle voltage of suitable phase, developed across the secondary winding 50 of transformer T, is applied to a pair of diode rectifiers 51 and 52. While the rectifiers 51 and 52 are shown specifically as diodes, it is to be clearly understood that they may be tubes of any other type. The essential thing is to utilize electron discharge devices at 51 and 52 which are adapted for connection as rectifiers of 60 cycle voltage. The cathode 53 of diode 51 and the 35. anode 54 of diode 52 are connected in common to the AFC lead 55, the charging condenser 56 being connected from the lead 55 to ground. The anode 57 is connected to the negative terminal of a direct current biasing source 58, and the 40. positive terminal of the current source 58 is connected to one end of the secondary winding 50. The cathode 59 of diode 52 is connected to the positive terminal of the direct current biasing source 60, whose negative terminal is connected to the opposite end of winding 50. The mid-point 45. of secondary winding 50 is connected by lead 61 and the secondary winding 62 of transformer T' to ground. The primary winding 63 of transformer T' is itself connected in shunt across the 50. 60 cycle current source 14. Accordingly, 60 cycle voltage is applied to the mid-point 50' of winding 50 by means of transformer T'.

55. The voltage sources 58 and 60 apply biasing voltage to each of the diodes 51 and 52 such that normally the rectifiers are cut off thereby to prevent charging of the condenser 56. That is, with no amplified 60 cycle voltage applied to transformer T the rectifiers 51 and 52 are cut off, since the 60 cycle voltage applied through the transformer T' is of insufficient magnitude to overcome the cut-off bias applied to each of the rectifiers. This situation exists, of course, when the voltage derived from the AFC detector and applied to grid 18 is of zero magnitude. It 60. is in this condition that there is developed zero 60 cycle voltage across output resistor 33 of tube 15. However, when there is developed a differential voltage across the output load of the AFC detector there will be developed 60 cycle 65. 70. 75. voltage across the secondary winding 50 of trans-

former T. When the voltage through transformer T combines with the voltage through transformer T' to overcome the cut-off bias of each of the rectifiers, then the condenser 56 will be charged by the rectified 60 cycle voltage.

Condenser 56 is chosen to have low losses so that it will hold its charge for a considerable length of time. If oscillator I takes on a detuned condition, the control voltage generated across condenser 56 is a direct current value just sufficient to shift the oscillator, by means of the reactance tube, the required amount to bring it back in tune. A condition of equilibrium is then obtained in which condenser 56 holds this fixed amount of charge. Of course, a loss-less condenser is unobtainable, but, in the practical case, a condenser may be obtained which will hold a charge as long as required. Hence, the AFC voltage over lead 55 is not necessarily alternating voltage.

Fig. 3 shows the relation between the alternating current voltages fed to diodes 51 and 52 and the control potential. In the balanced condition the voltage fed to each diode comprises only that obtained from transformer T', which gives a voltage corresponding to amplitude a in Figure 3. When a control voltage is applied to lead 26, the voltage amplified by the phase reverser and amplifier opposes the voltage from transformer T' at one diode input, and aids that fed to the other diode. As a result, the application of a control potential raises the input to one diode and lowers that to the other. By means of this amplifying arrangement, the response to the control potential may be made very sensitive.

Diodes 51 and 52 are normally biased by means of batteries 58 and 60 so that current is not drawn for amplitudes of input lower than the value a . Hence, for the in-tune condition, at which both inputs will have the amplitude a , condenser 56 will remain in its uncharged condition. When a positive control potential is applied the input to diode 51 increases, and that to diode 52 lowers. This causes diode 51 to draw current, and charge condenser 56 in a direction which places a positive potential on lead 55. When a negative control potential is applied, the input to diode 52 rises and that to 51 lowers. This causes diode 52 to draw current in a direction which tends to charge condenser 56 negatively. If a positive charge is already on 56, the result of this negative charge will be a reduction of the positive charge. It is thus seen that as the control potential is made positive or negative, the charging voltage applied to the condenser is, also, made positive or negative. For the in-tune condition charging current does not flow to the condenser, and it holds to the value of charge which was last applied to it.

The charging voltage developed across condenser 56 is employed to control the gain of any suitable form of electronic reactance tube. The numeral 70 denotes such a tube. The circuit connections between tube 70 and the tank circuit 2 of the controlled oscillator I are well known. It is to be clearly understood that the AFC voltage may be applied over lead 55 to any suitable and well known form of reactance tube circuit. Without going into specific details of the reactance tube circuit, it is pointed out that the pentode tube 70 has its plate to cathode impedance connected in shunt across the tank circuit 2 by a connection from plate 71 to the high alternating potential side of tank circuit 2 through the direct current blocking condenser 72. The cathode 73

is connected to ground through a suitable biasing resistor 74.

The tank circuit 2 is, furthermore, shunted by a suitable phase shifter network. In this case, 5 the phase shifter network consists of resistor 75 in series with a condenser 76. The oscillatory current flowing in tank circuit 2 develops a voltage across the condenser 76, which is in phase quadrature with the voltage across tank circuit 2. 10 Suitable design of the magnitudes of resistor 75 and condenser 76 permits this phase quadrature shift to be secured. It is specifically desired that the magnitude of resistor 75 be relatively large compared to the reactance of condenser 76. The 15 phase-shifted voltage across condenser 76 is applied to the grid 89 of tube 70, and the grid is connected to the ungrounded terminal of condenser 76 through a direct current blocking condenser. The AFC lead 55 is connected to the grid 20 89 through the filter resistor 90. Suitable positive potential is applied to plate 71 through a radio frequency choke coil 91.

When the tube 70 has normal gain, that is with no bias applied over lead 55, the plate to cathode 25 impedance of tube 70 simulates an inductive reactance across tank circuit 2. The magnitude of this simulated inductive reactance depends on the magnitude of the voltage existing at the ungrounded terminal of condenser 56. The sense 30 of change of the inductance reactance is dependent on the polarity of the charging voltage across condenser 56. Hence, there is provided an effective and simple means for change of frequency at tank circuit 2 to compensate for the frequency 35 shift of the modulated carrier energy at circuit 6 from the predetermined reference frequency. It is to be clearly understood that the control voltage applied over lead 55 will vary the magnitude of the simulated inductive reactance in a direction and to an extent such that the frequency of circuit 2 is changed sufficiently to cause the frequency of the converter output substantially to coincide with the predetermined reference frequency of circuits 6 and 8. It will now be appreciated that frequency shifts at the input of the AFC detector are translated into corresponding variations in phase and amplitude of 60 cycle 40 voltage across resistor 33. The latter are translated into variations in the AFC voltage delivered 45 over lead 55.

This invention is not limited in inertia effects, as in prior motor control. In the motor type of control a limitation in speed of operation is obtained in that as the control calls for direct 55 changes in direction of rotation of the motor shaft, the inertia of the motor rotor must be overcome. This inertia inherently slows down the speed with which the control will respond to a control potential. It, also, may cause overshooting of the control which leads to hunting. In this present electronic system, however, charging current is fed to condenser 56 in a low resistance circuit which builds up the charge on the condenser rapidly. When the condenser is not being charged the diodes do not conduct, so that the condenser holds its charge for a length of time determined by its losses. The result is quick response to a control potential.

In the case of the transmitter system of Fig. 2 the lead 55 is preferably modified as is indicated. Modulation potentials are applied to the reactance tube 70 to effect frequency modulation of the carrier energy of the master oscillator I'. This is done by injecting the modulation voltage 70 across a resistor 55' in series in line 55. The

secondary of the input transformer M is connected across resistor 55'. Those skilled in the art of radio communication are fully aware of the manner in which the modulating potentials from any desired source of modulation voltage (say audio) cause the tube 70 to vary the frequency of circuit 2 to create a corresponding frequency modulation of the master oscillator. The AFC circuit, being responsive to relatively slow frequency shifts at circuit 6, 8 will not interfere with the modulating function.

In Fig. 4 I have shown another method of applying the principle of my invention. In addition, a different diode system is employed in place of the diode network 51, 52 of Fig. 1. In Fig. 4 the selective amplifier 5 has its discriminator output circuit 6, 9, 8 coupled to a pair of electron discharge tubes 100, 101. The cathodes of tubes 100, 101 are tied in common to ground, while a suitable direct current source 102 has its ungrounded negative terminal connected to the midpoint of input coil 8' through choke coil 13'. The opposite ends of coil 8' are connected to respective input grids 100' and 101' of tubes 100 and 101. The respective plates 111 and 112 of tubes 100 and 101 are connected to the respective primary circuits 113 and 114 of transformers 103 and 104.

A pair of double diode tubes 107 and 108 are utilized. The tube 107 has a pair of reversely connected diodes D₁ and D₂, while tube 108 is provided with reversely connected diodes D₃ and D₄. The anode of diode D₁ and cathode of diode D₂ are connected in common through condenser 105 to the high potential side of secondary circuit 115 of transformer 103. The cathode of diode D₁ is connected to the grounded side of input circuit 115 through the direct current source 109'. The anode of diode D₂ is connected to the AFC lead 55.

The cathode of diode D₃ and anode of diode D₄, in the case of the second tube 108, are connected in common through condenser 106 to the high potential side of secondary circuit 116 of transformer 104. The low potential sides of both input circuits 115 and 116 are grounded, and the anode of diode D₃ is connected to the ungrounded negative terminal of the direct current source 110. The condenser 56 is connected from the common connection 117 between the anode of diode D₂ and cathode of diode D₄ to ground.

The diode arrangement is a counter circuit in which each half cycle of alternating current voltage applied to the input causes a small amount of charge to be applied to condenser 56. The operation is the same as a voltage-doubler rectifier, except that condenser 105 is made small compared to 56. For instance, in the case of diode 107, the positive half cycles draw current through diode D₁ which charges condenser 105. No current is drawn by diode D₂ for the positive half cycle. The negative half cycle draws current through diode D₂ to place a charge on condenser 56 which is dependent on the relative magnitudes of condensers 105 and 56. Since condenser 105 is usually much smaller than condenser 56, many half cycles of alternation are required before condenser 56 receives its full charge corresponding to twice the peak voltage of the applied alternating wave. Hence, the applied voltage must be left on a certain length of time to bring condenser 56 up to its full charge.

Amplifiers 100 and 101 take the outputs of discriminator 6, 8, 9, and amplify them in accordance with the characteristic of Figure 5.

Bias is applied from battery 102 so that amplifier 100 produces output only for frequencies above the carrier frequency F_c. For lower frequencies, the discriminator output does not overcome the bias. Amplifier 101 amplifies the other half of the discriminator output, so that it furnishes input to diode 108 that is zero for frequencies above F_c and rises as the frequency is made lower than F_c. As a result of this cut-off adjustment of the amplifiers, a frequency shift away from frequency F_c feeds input to either diode 107 or 108 depending upon the direction of frequency shift. This charges condenser 56 with a voltage which depends on the direction and magnitude of the frequency shift. For the in-tune condition neither diode draws current so that the condenser remains at the charge it last received.

The function of batteries 109' and 110 is to apply a delay bias to diodes D₁ and D₂ so that condenser 56 does not discharge to ground through the series circuits comprising diodes D₂, D₁ and D₄, D₃. This delay bias has a magnitude approximately equal to the magnitude of voltage charge applied to condenser 56. For instance, if the maximum range of positive charge applied to condenser 56 is 5 peak volts, battery 109' should have a value of 5 volts. Likewise, if the maximum negative excursion of condenser 56 is 5 volts, battery 110 should have a value of 5 volts. (This same relation exists in the circuit of Figure 1 in the case of batteries 53 and 60). The result of this delay bias is to produce an idle interval in the control potentials applied to condenser 56. However, the idle interval may be made negligibly small by the application of high levels of diode input from amplifiers 100 and 101.

The present system of AFC, as shown in Fig. 1, is applicable to frequency-shift telegraph reception as disclosed in my application Serial No. 491,106 filed June 17, 1943, now Patent Number 2,462,470, dated February 22, 1949. In that patent I have generally disclosed an improved telegraph receiver for FM telegraph signals which includes an AFC circuit which maintains the tuning of the receiver at a fixed frequency with respect to either the mark or the space frequencies, and which frequency control circuit 50 will not tend to follow the mark or space frequency. There is employed means for converting the output of a conventional FM detector, or discriminator-rectifier, from the square wave form that is obtained in frequency shift telegraph reception, to a control potential which is proportional to the deviation in mean frequency of the received signal. This is accomplished by means of a limiter and combiner circuit, as schematically represented in present Fig. 6.

The rectangle 201 is representative of a conventional FM detector preceded by a suitable I. F. input circuit, say of the type shown in Fig. 5 of my last-mentioned application. It delivers normally a square wave output for telegraph reception, as disclosed in said application. Such a square wave output is not suitable as an AFC potential. Hence, by limiting the output of detector 201 in a suitable limiter 202, and recombining with the output of the detector in phase opposition in combiner 203, the characteristic at the output terminals appears as shown in Fig. 7. It will be noted that limiter 202 and combiner 203 are schematically represented. Reference is made to my last-mentioned application for specific circuits which may be employed,

11

and more especially reference is made to Fig. 5 of said application. The output voltage at leads 300 may be utilized for connection to resistors 25 and 20 respectively of present Fig. 1. That is, the output from leads 300 is equivalent to the output across 12, 12' in Fig. 1. The benefits of the present AFC method are thus applicable to the telegraph receiver of my aforesaid application.

In further explanation of this application of my invention, it will be noted that this discriminator characteristic has two values, F_1 and F_2 , at which the in-tune condition is obtained. The telegraph signals would normally be tuned so that the space frequency is at the F_1 position, and the mark frequency at the F_2 position, or vice versa. With this type of discriminator characteristic, a drift in the frequency produces a control potential which is proportional to the drift, regardless of whether the keying is in the mark or space condition. The result is a control potential for automatic frequency control which has the same characteristic as that obtained directly from the discriminator when the ordinary program, or voice modulation is used.

While I have indicated and described several systems for carrying my invention into effect, it will be apparent to one skilled in the art that my invention is by no means limited to the particular organizations shown and described, but that many modifications may be made without departing from the scope of my invention.

What I claim is:

1. In combination with a high frequency oscillator having means for adjusting the frequency thereof, an electronic reactance tube including connections to the oscillator for providing control over the oscillator frequency, a source of alternating voltage, a pair of rectifiers connected in series-aiding relation, means for individually biasing the rectifiers to cut-off, means for applying alternating voltage from said source to both of said rectifiers, a discriminator rectifier network having an input circuit responsive to oscillator frequency shifts, said network including an output circuit constructed and arranged to develop a direct voltage representative of said frequency shifts, an electron control device having at least two spaced control electrodes, means for applying alternating voltage from said source to said spaced electrodes in such relative magnitude that output voltage derived therefrom is normally zero, means for applying said direct voltage to at least one of the spaced control electrodes, means for applying to said rectifiers output voltage derived from the control effect of said spaced control electrodes, and additional means responsive to the joint output of said rectifiers for controlling the effect of said reactance tube.

2. In a system of the type including an oscillator provided with a tank circuit whose frequency is to be controlled, a converter adapted to have signals and oscillations from said oscillator applied thereto, and a selective amplifier responsive to the converter output, a detector for translating frequency shifts of the output of the selective amplifier into corresponding control voltage variations, a source of low frequency voltage, means responsive to said low frequency voltage and said control voltage variations for providing effective low frequency voltage whose phase and amplitude is representative of said frequency shifts, a pair of rectifier devices, means for normally rendering

12

said rectifier devices inoperative, means for applying said low frequency voltage from said source as a reference voltage to said rectifier devices, means for applying the variable phase and amplitude low frequency voltage to said rectifier devices thereby to provide a resulting voltage whose magnitude and polarity is a function of said frequency shifts, and means for using said resulting voltage to control the frequency of said tank circuit.

3. In a system of the type including an oscillator provided with a tank circuit whose frequency is to be controlled, a converter adapted to have signals from a signal source and oscillations from said oscillator applied thereto, and a selective amplifier responsive to the converter output; a detector for translating frequency shifts of the output of the selective amplifier into corresponding control voltage variations, a source of low frequency voltage, means responsive to said low frequency voltage and said control voltage variations for providing effective low frequency voltage whose phase and amplitude is representative of said frequency shifts, a pair of rectifier devices, means for normally rendering said rectifier devices inoperative, means for applying said low frequency voltage from said source as a reference voltage to said rectifier devices, means for applying the variable phase and amplitude low frequency voltage to said rectifier devices thereby to provide a resulting voltage whose magnitude and polarity is a function of said frequency shifts, means for using said resulting voltage to control the frequency of said tank circuit, said means responsive to the control voltage and said low frequency voltage comprising an electron control device having at least two control electrodes, means for applying the low frequency voltage to said control electrodes in different magnitudes, and an additional connection for applying said control voltage to one of said control electrodes.

4. In combination with a high frequency oscillator having means for adjusting the frequency thereof, an electronic reactance tube including connections to the oscillator for providing control over the oscillator frequency, a pair of rectifiers connected in series-aiding relation, means for individually biasing the rectifiers to cut-off, means for applying alternating current voltage to both of said rectifiers, a discriminator rectifier network having an input circuit responsive to oscillator frequency shifts, said discriminator network having an output circuit in which is developed a rectified voltage representative of said frequency shifts, means for applying said developed rectified voltage to said first-named applying means to vary the alternating current voltage applied to said rectifiers as a function of said frequency shifts, capacitive means connected to be charged by the output of said rectifiers, and means connecting said capacitive means to said reactance tube to control the effect thereof in response to the charge on said capacitive means.
